UNITED STATES PATENT OFFICE.

ISAAC H. ATHEY, OF CHICAGO, ILLINOIS.

ANTIRATTLING DUST AND WEATHER GUARD FOR WINDOWS.

965,851.

Specification of Letters Patent. Patented Aug. 2, 1910.

Application filed November 23, 1908. Serial No. 463,959.

To all whom it may concern:

Be it known that I, ISAAC H. ATHEY, a citizen of the United States, and a resident of the city of Chicago, in the county of Cook and State of Illinois, have invented certain new and useful Improvements in Antirattling Dust and Weather Guards for Windows; and I do hereby declare that the following is a full, clear, and exact description 10 of the same, reference being had to the accompanying drawings, and to the letters of reference marked thereon, which form a part of this specification.

Of the very numerous devices sometimes used for weather proofing windows, and the like, none may be said to operate satisfactorily in all respects. In some, rubber coated fabric engaged to wooden strips are nailed to the blind stop against the sash. These, 20 while serving the purpose for a short time, soon become practically useless owing to the rubber fabric becoming affected by the atmosphere thereby losing its resiliency and as a result, instead of engaging the sash positively, lies away from the same failing utterly in the object for which used. In many other constructions, metallic window guards have been employed. These usually are constructed of strips of metal engaged 30 upon the sliding sash and on the frame and coacting to afford a positive metallic contact face to face at all times. In these constructions the constant friction due to raising and lowering the window soon wears away whatever anti-rusting coating may be 35 provided on the strips, leaving the same free to rust and with the rusting and continuous wear due to friction, such devices have proven very short lived and soon fail 40 to exclude either dust or wind and often prove exceedingly noisy.

The object of this invention is to provide a dust and weather guard adapted for use not only for windows but for all constructions 45 in which one element slides upon another affording a joint therebetween from which it is desired to exclude the passage of air and dust.

It is also an object of the invention to afford a construction reducing friction to a minimum and in which metallic contact between moving parts cannot readily occur.

It is a further object of the invention to afford in a device of the class described a resilient packing adapted to be engaged in one 55 of the elements to which the guard is to be

applied and adapted to positively and yieldingly engage a complemental element slideable therein and engaged to the other element.

Finally it is an object of this invention to afford an exceedingly cheap, durable and effective anti-rattling weather and dust guard, capable of being very quickly and easily applied by one not previously skilled 60 and when installed, not capable of being injuriously affected by moisture and subject to practically no deterioration from use.

The invention consists in the matters hereinafter described and more fully pointed out 70 and defined in the appended claims.

In the drawings: Figure 1 is a fragmentary perspective view of a part of a window frame and the upper and lower sliding sash therein. Fig. 2 is a section taken on line 75 2—2 of Fig. 1. Fig. 3 is a perspective view of the female member of the guard. Fig. 4 is a fragmentary perspective view of the male element of the guard. Fig. 5 is a fragmentary view in vertical section taken 80 through the parting rails and illustrating a modified form of guard adapted to be engaged therebetween.

As shown in the drawings: A, indicates the jamb of the window frame, and B, the 85 parting bead or strip; B', the blind stop, and B'', the inner stop, said parting strip, blind stop and inner stop engaging therebetween the lower sliding sash C, and the complemental upper sliding sash C', in the 90 usual manner.

As shown, each of the sash is provided with devices embodying my invention comprising, as shown, a male member D, adapted to be engaged to the frame and a female 95 member E, adapted to be set in the sash. As shown, the male member D, is constructed of sheet metal coated in any suitable manner and with any suitable material to render the same rust proof and as shown, is bent to Z 100 bar form affording a flange d, adapted to be engaged to the frame by insertion in the channel for the parting strip, as shown in Figs. 1 and 2, affording a flat web d', bent at right angles with said flange and adapted 105 to lie flat against the face of the jamb and of a width depending upon the position of the female member on the sash. At the opposite edge of the web d', is provided a flange d'', having, as shown, a rounded edge formed 110 by rolling the metal over to afford double thickness for the entire width of the flange.

In securing said male member upon the frame, the parting bead serves as a guide and the flange d , being engaged to the frame thereby insures the flange d^2 , being at all 5 times in parallel relation. The side rails of the sash are each plowed or grooved at a distance from the parting bead face thereof corresponding with the distance of the male flange d' , from the parting strip, the depth 10 of said groove in the sash and the width thereof being sufficient to receive therein the female member E, constructed, as shown, of a sheet of metal similar to that before described, bent or rolled transversely to afford 15 a narrow channel having deep flanges, the edges e , of which are rolled inwardly to positively grip and engage the edges of a strip of felt e' , which lines said channel for its entire length. The width between the 20 flanges of the channel E, is sufficiently greater than the thickness of the male flange d^2 , to insure the fabric lining the channel pressing upon said flange at all times, as shown in Fig. 2. The depth of the channel 25 is, of course, sufficiently greater than the width of the flange d^2 , to avoid undue pressure on the fabric or felt lining, though insuring at all times sufficient pressure on the sides and inner edge of said flange from said 30 fabric to afford an effective packing.

The construction illustrated in Fig. 5, comprises an angle bar F, formed of sheet metal, the edges f , of which are turned outwardly over a strip of fabric f' , to engage 35 the same thereto and which longitudinally of the bar at the center is left sufficiently full, as shown at f^2 , to receive therein a packing material f^3 , more or less resilient so that when the said angle bar is engaged 40 for instance, upon the lower inner horizontal angle of the upper sash, said packing bears against the outer face of the top rail of the lower sash.

The operation, from the construction described, is obvious. In installing, the anti-rattling dust and weather proofing device shown in Figs. 1 to 4 inclusive, the side rails of the sash are first plowed at suitable distances from the faces thereof, which bear 45 against the parting strip and the female member or lined channel E, is pressed therein. The seat for the parting strip on the outer side from the top downwardly to about the middle of the frame, is increased in 50 width by any suitable tool if necessary to receive therein the flange d , of the Z bar strip or male member, and in a similar manner the seat is increased on the inner side of the parting strip for the lower sash. Suitable lengths of each of said members having 55 been each secured as before described, the flange d^2 , holds the sash from rattling under any condition owing to the pressure of the felt or fabric on the sides thereof. Wind 60 and dust are positively excluded and in any

event, although not hermetically excluding the air, any particles of dust carried therewith are filtered out by the felt or fabric, thus under all conditions performing the function for which designed. 70

Of course, while I have described the device as applicable to windows, it may be used for other purposes, and, owing to its dust excluding qualities, and its prevention of the rattling of the sash, it is particularly 75 applicable and important not only for windows generally but for car windows and numerous other purposes which are plainly evident from the construction.

Of course, details of construction and the 80 method of securing the parts in place may be varied, and I therefore do not purpose limiting this application for patent otherwise than necessitated by the prior art.

I claim as my invention:

1. In a window the combination with the frame and the sliding sashes having grooves in the stiles thereof, of a sheet metal channel member secured in each groove, a lining of fabric in the channel providing parallel 90 strips of fabric and an angle bar secured to the frame by one flange and having another flange extending between the strips of fabric. 95

2. In a window the combination with the frame and sliding sashes having longitudinal 95 grooves in the stiles thereof, of a bar secured to the frame having an outwardly projecting flange, a metallic member secured in each groove in the stiles of the sashes and a lining in said metallic member bearing 100 against opposite sides of the flange of said bar and slidably relatively thereof.

3. The combination with a frame and its parting strip of a sheet metal Z bar engaged at one flange in the seat for the parting strip and with the other flanges standing outwardly and at a distance from the parting strip, a sliding member in the frame, a narrow sheet metal channel bar seated in the side of the sliding member in position to 110 engage the projecting flange of the Z bar and a lining of felt permanently secured in the channel and pressing on both sides of said flange. 105

4. A device of the class described embracing a Z bar of coated sheet metal and having one thick flange and one thin flange, the thick flange being formed by turning the edge thereof over to afford double thickness for the entire width and a female member 120 complementary with said thick flange embracing a strip of coated metal rolled to afford a narrow channel, a lining of fabric therein, the edges of the flanges of said channels being rolled inwardly to permanently 125 engage the fabric, the width of said channel being such as to insure the fabric pressing at all times on the male flange.

5. A weather guard for windows comprising relatively movable interfitting me- 130

metallic members and a fabric lining between said movable members.

6. A weather guard comprising relatively slidable metallic members and a strip of fabric secured to one of the members and engaging the sides of the movable member to exclude dust and moisture.

7. In a device of the class described the combination with a window and jamb of a 10 metallic member secured to the jamb, a sliding metallic member secured to the stile of the window and interfitting the member secured to the jamb and a fabric lining secured to the sliding member and bearing 15 against the sides of the other member.

8. A guard for windows comprising slid- 2
able channel members secured to the stiles of the window sashes, members secured to

the window jamb and engaging in the channel members and a fabric lining for providing a dust and moisture proof joint between the sliding joint of the members.

9. A weather guard embracing a movable channel member, a fabric lining for the movable channel member providing a central pas- 2
sage and an angle member having one flange engaged in the central passage formed by the fabric strip.

In testimony whereof I have hereunto subscribed my name in the presence of two sub-
scribing witnesses.

ISAAC H. ATHEY.
